RECIPROCATING VALVE

Charles Burnham, Washington, D. C., assignor of
one-half to Ralph Burnham, Pasadena, Calif.

Application August 24, 1934, Serial No. 741,314

3 Claims. (Cl. 251—28)

This invention relates to that type of valve in which a beveled valve seats against a beveled seat, and the main object of this invention is to provide a simple and inexpensive means whereby, when the valve is open, wire-cutting of the seat is entirely avoided, thereby maintaining the valve in a non-leakage condition for a great length of time, as more fully hereinafter set forth.

Referring to the drawings annexed, Fig. 1 is a vertical sectional view of the valve showing the valve closed;

Fig. 2 is a similar view showing the valve moved to a position where it is about ready to open;

Fig. 3 is a horizontal sectional view through the valve;

Fig. 4 is an exploded view of the internal parts of the valve; and

Figs. 5 and 6 are views of the details hereinafter described.

Figs. 7, 8, and 9 are views showing modifications. Referring to the drawings by reference characters, 10 designates the valve casing having the usual valve chamber provided with the usual diaphragm 11 extending across its interior and provided with a threaded opening in alignment with an upstanding tube 12 having communication with the chamber 10. Nicely fitting the interior of the tubular extension 12 is a tube 13 whose upper part is interiorly threaded at 14, and which, at a point just below said threaded part 14, is provided with an annular series of ports 15. Just below the ports 15, the tube 13 is provided with a shoulder 16 which faces downwardly and is adapted to bear upon the upper, horizontal face of the division wall 11. At a point below the shoulder 16, the tube is reduced in diameter and externally threaded for engagement with the internal threads in the opening in the division wall 11. At a point below this threaded portion 14 of the cylinder 13, the cylinder is again reduced in diameter and provided with another annular series of ports 17, and below the ports 17 the cylinder fits nicely the inner face of the wall of a pocket 18 formed integral with the chamber 10 and closed all around. The portions are such that when the cylinder 13 is screwed down into the division wall then the lower, reduced end of the cylinder 13 makes a water and steam tight connection with the bottom wall of the pocket 18 by being pressed against a lead or other washer 19 resting upon the bottom of the pocket.

On top of the tube 12 and clamped by means of a ring nut 20 is an annular flange 21 formed on the lower end of the cap 22 which carries a stuffing-box and packing gland of the usual con-

struction, through which the usual rotatable, slideable valve stem 23 extends. On its lower face the cap 22 is provided with an annular series of lugs 23 which extend down into the tube 12 and between cooperating upstanding lugs 24, extending upwardly from the upper edge of the tube 13, and the body of the member 22 is provided with a nut formation 25 whereby by the use of a wrench applied to the nut formation 25 the cap 22 may be utilized for screwing in or screwing out the cylinder 13, the ring nut 20 being of course first removed to permit this operation. By thus screwing down the cylinder 13, the threaded portion thereof engages the internal threads in the hole in the division wall 11, shoulder 16 is pressed hard against the division wall and the extreme lower end of the cylinder is forced down hard against the washer or ring 19, thus rendering the joints water and steam tight.

The stem 23' at its lower, inner end is provided with a threaded enlargement 25' which fits the threaded interior of the seat-tube 13 and swivelly connected to the lower end of the stem is a valve disk 26, this swivel connection being accomplished by a headed pin 27 projecting upwardly from the upper face of the disk 26 and engaged in an open notch 28 formed in the bottom wall of a claw-like short cylinder 29 formed integral and depending from the lower side of the threaded enlargement 25. By means of this connection between the valve disk 26 and the stem, the valve disk and stem will have an independent rotative action to thus insure the proper opening and closing of the valve disk. The valve disk seats against a beveled seat 30 formed in the seat-tube 13 at a point just below the ports 15.

Formed integral with and depending from the valve disk 26 is a cylindrical supplemental valve or secondary valve-tube 31 whose exterior nicely fits the interior face of the lower part of the tube 13 so as to be capable of opening as well as closing the inlet ports 17, and at a point where this valve-tube 31 joins the valve disk 26, this tube is provided with an annular series of outlet ports 32, which, when this valve-tube is raised, puts the interior of the tube into communication with the outlet ports 15. The sizes and positions of the ports 17 and 32 and the length of the valve-tube 31 are such that when the main valve 26 is seated both these sets of ports are closed, as shown in Fig. 1. And when the main valve is moved upwardly to open position, the inlet ports 17 are kept closed by the tubular secondary valve 31 until the upper edge of the valve-tube 31 (which forms the lower edges 31' 55

of the ports 32) has been raised high enough to serve as a guard or fender for the valve seat 30, as shown in Fig. 2, thereby completely preventing the out-rushing fluid from wire-cutting 5 said seat 30. It will be noted that the main valve cannot even be cracked without being fully protected against wire-cutting.

In the modifications shown in Figs. 7 and 8, the cylinder 13 is not threaded into the passage 10 through the diaphragm 11, but instead is seated against a beveled seat therein, and instead of the interlocking lugs 23, 24 for rotating the cylinder 13 to screw it into place, I extend the top edge of the cylinder 13 high enough to abut directly 15 against the cap 22 so that when the threaded ring 20 is screwed down onto tube 12 the cylinder 13 will be jammed hard into place, with its beveled part against the seat and diaphragm 11 and its lower end against the washer ring or 20 disk 19. In this form of device, it is desirable to use a washer 35 between the member 22 and the upper end of the tube 13.

In this modification I show also a slight modified form of the main valve. In this form the head 36 of the combined supplemental valve and 25 guard 31 is provided with a central threaded opening down through which is screwed a pin 37 formed integral with the head 27, this threaded pin or extension 37 serving to clamp on top of the head 36 a flanged disk 38, a seat washer 39 being clamped between these two parts 36 and 38. This seat washer 39 faces directly downward and is adapted to seat against an upwardly-facing valve seat formed on the cylinder 13 instead of the beveled valve seat shown in the other figures. In this construction as in the form shown in the other figures the distance between the lower edge of the valve cylinder 31 and the bottom edges 31' of its outlet ports is 35 such that these bottom edges are raised to a protective position with respect to the valve seats before the inlet openings 17 are opened. It is desirable that the lower end of the screw pin 37 shall be tapered in order to divide the up-going 40 stream of fluid and divert it equally through the ports 32.

In Fig. 9 I illustrate one way of insuring a fluid-tight joint between the valve-tube 31 and its guide tube 13. For this purpose, I provide a 50 groove in the inner face of the wall of the tube 13 and place therein a split piston ring 40 of common form, this ring being of course so located that in all adjustments of the valve tube,

the tube will lap this ring. With a packing ring of this sort, the main valve 26 may be cracked without danger of fluid leaking up behind the guard to the valve seat 30, thus insuring against wire-cutting of the seat even when the main valve 5 is cracked to the most minute degree. For convenience in assembling, the lower part 13' of the tube 13 may be made separate from the main part of the tube and screwed into its lower end to thus form an annular cavity for the packing 10 ring, and also the top inner corner of the packing ring and the lower outer corner of the tubular part 31 may be slightly beveled to enable the valve to be readily inserted down into its guide tube 13' when the parts are assembled. 15

I claim:

1. In combination, a valve casing having an upstanding tube exteriorly threaded, a hollow cylinder slidably fitting down into said tube and provided with a valve seat surrounding the passage through the casing and internal threads and having an opening communicating with the outlet of the casing, a ring nut screwed on the threaded part of said tube, a cap having a flange which is clamped on the top end of said tube by 25 said ring nut, said cap having a nut formation above the flange adapted for the use of a wrench, interlocking lugs between said cap and the upper end of said cylinder, and a slideable-rotatable stem extending down through said cap and provided with a threaded member for engaging the internal threads of said cylinder and a valve. 30

2. In combination, a valve casing having a passage and a valve-seat member therein and also a closed cylindrical portion below said member, a 35 cylinder supported on and attached to said member, the lower end of this cylinder depending into and fitting the interior of said cylindrical portion of the casing, the part of this cylinder between said cylindrical portion and the valve-seat 40 being provided with an inlet port, a main valve and means for moving it toward and from said seat, this main valve being provided with a depending cylindrical supplemental valve fitting into the aforesaid cylinder and having an outlet port at its upper end and its lower end open. 45

3. The structure in accordance with claim 2, the lower end of said cylinder being open and a packing being employed between said lower end of the cylinder and the bottom of the closed cylindrical portion of the casing. 50

CHARLES BURNHAM.
